United States Patent Office

Des. 203,773
Patented Feb. 15, 1966

203,773

PACKAGING TRAY

Franklin W. Weiss, Longmeadow, Mass., assignor to Plastic Packaging Corporation, Chicopee, Mass.

Filed Dec. 14, 1964, Ser. No. 83,012

Term of patent 14 years

(Cl. D58—13)

FIG. 1

FIG. 2

FIG. 1 is a top plan view of a packing tray embodying my new design; and

FIG. 2 is a side elevational view thereof.

I claim:

The ornamental design for a packaging tray, as shown.
